UNITED STATES PATENT OFFICE.

FRANK R. PERRY, OF CHICAGO, ILLINOIS.

CONDENSER FOR AUTOMOTIVE-VEHICLE ENGINE RADIATORS.

Application filed November 8, 1924. Serial No. 748,547.

The purpose of this invention is to provide means for avoiding the wastage of the circulatory cooling medium of an internal combustion engine which ordinarily occurs by evaporation and escapes in the form of vapor from the radiator upon overheating. It consists in the elements and features of construction shown and described as indicated in the claims.

10 In the drawings:

Figure 1 is a vertical section of a condenser embodying this invention indicated as mounted at the overflow connection of the radiator of an automobile engine, showing 15 the expandible and reducible chamber of the condenser fully expanded.

Figure 2 is a similar view showing said chamber in collapsed condition.

The structure shown in the drawings comprises an expandible and reducible chamber which, as illustrated, is in the form of a bellows, A, preferably constructed as to its collapsible wall, of elastically stretchable material such as sheet rubber, and comprising a 20 fixed head, B, which in the form shown is the bottom of the chamber, and a movable head, C, which in the form shown is the top of the chamber, this bellows having its cavity connected by means of a nipple, b, which terminates the bottom head, B, for connection with the overflow nipple, E, of the radiator to be served. The movable head is weighted as indicated by the thickness shown, a hard 25 wood board of moderate thickness or a metal plate of the thickness indicated by the drawing, serving this purpose adequately in respect to weight. It will be understood that normally the bellows is collapsed by the weight of the movable head as shown in Figure 2, and that upon the generation of vapor in the radiator developing some pressure, vapor will pass into the bellows chamber causing it to be expanded, lifting the movable head, and that this expansion to the 30 extent of the capacity of the bellows at its most expanded condition will accommodate the vapor generated by heating the circulatory fluid, customarily a mixture of alcohol and water, which will be retained in the expanded bellows and there condensed by reason of the exposure of the chamber to exterior atmospheric temperature conditions, the liquid of condensation flowing back into

the radiator, so that a bellows of limited size will take care of the vapor generated throughout a considerably long condition of overheating of the engine, because of the constant re-condensation and return flow of the liquid into the radiator. To provide against extreme overheating and vaporization of the circulatory fluid, a vent port, D, is provided through the top movable member of the bellows, controlled by a valve, D¹, held normally seated by the tension of the spring, F, which may be adjusted by a screw, G, to permit the valve to open and relieve the pressure in the bellows at any desired stage of pressure. Preferably the entire bellows constituting the expandible and reducible chamber is enclosed in a protective casing, H, mounted rigidly with respect to the fixed head B, of the bellows. This protective casing is preferably provided with apertures as shown at h, h, for ventilation to facilitate the radiation from the expandible and reducible chamber necessary for cooling and the condensation of the vapor.

I claim:

1. A device for the purpose indicated, comprising an expandible and reducible chamber adapted for communication with a source of vapor to be condensed, said chamber being normally reduced and adapted to expand under the pressure of the vapor developed at the vapor source and discharging into said chamber, said chamber being exteriorly exposed to atmospheric cooling for condensing the vapor and permitting reduction of the chamber.

2. In the construction defined in claim 1, the expandible and reducible chamber being in the form of a collapsible and expandible bellows having one head fixed and the other head free to move toward the fixed head upon reduction of the volume of the vapor by condensation.

3. In the construction defined in claim 1, the expandible and reducible chamber being in the form of a vertically collapsible and expandible bellows having the lower head fixed and the upper head heavy and free to move in the collapse of the bellows upon cooling and condensation of the vapor admitted thereto.

4. In the construction defined in claim 1, the expandible and reducible chamber having

its enclosing wall made in part at least of elastically stretchable material, as rubber sheeting.

5. In the construction defined in claim 1, the expansible and reducible chamber being in bellows form having a fixed lower head and a heavy upper head, and free to move in the collapse and expansion of the bellows

element connecting the two heads, being made in part at least of elastically stretchable material, as rubber sheeting. ¹⁰

In testimony whereof, I have hereunto set my hand at Chicago, Illinois, this 6th day of November, 1924.

FRANK R. PERRY.
